NEWEL POST FOR BOWLING BALL RACKS OR THE LIKE

Robert I. Anderson, Muskegon, Mich., and Ernest F. Thomson, Tuckahoe, N. Y., assignors to The Brunswick-Balke-Collender Company, Chicago, Ill., a corporation of Delaware

Application February 2, 1949, Serial No. 626
Term of patent 14 years

(Cl. D34—5)

To all whom it may concern:

Be it known that we, Robert I. Anderson and Ernest F. Thomson, citizens, respectively, of the United States and the Dominion of Canada, and residents, respectively, of Muskegon, in the county of Muskegon, State of Michigan, and Tuckahoe, in the county of Westchester, State of New York, have jointly invented a new, original, and ornamental Design for a Newel Post for Bowling Ball Racks or the like, of which the following is a specification, reference being had to the accompanying drawings, forming a part thereof, in which:

Fig. 1 is a front elevational view of a newel post for bowling ball racks or the like, showing our new design;

Fig. 2 is a side elevational view thereof looking at the righthand end of Fig. 1;

Fig. 3 is a rear elevational view thereof; and

Fig. 4 is a top plan view thereof.

The dominant features of the design are shown in full lines.

We claim:

The ornamental design for a newel post for bowling ball racks or the like, as shown and described.

ROBERT I. ANDERSON.
ERNEST F. THOMSON.
